UNITED STATES PATENT OFFICE

147,483

DESIGN FOR A JUICE EXTRACTOR

Vytant Aleks, Rockford, Ill., assignor to Ebaloy,
Incorporated, Rockford, Ill., a corporation of Illinois

Application February 4, 1946, Serial No. 126,230

Term of patent 14 years

(Cl. D89—1)

To all whom it may concern:

Be it known that I, Vytant Aleks, a citizen of the United States, residing at Rockford, in the county of Winnebago and State of Illinois, have invented a new, original, and ornamental Design for a Juice Extractor, of which the following is a specification, reference being had to the accompanying drawings, forming a part thereof.

In the drawings:

Fig. 2 is an end view.

Fig. 3 is a side view.

I claim:

The ornamental design for a juice extractor, substantially as shown.

VYTANT ALEKS.
